(57) **CLAIM**

The ornamental design for a forming panel insert, as shown and described.

DESCRIPTION

FIG. 1 is a top, front, left perspective view of a forming panel insert showing my new design;

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is an enlarged view of FIG. 6;

FIG. 8 is a right side view thereof;

FIG. 9 is an enlarged view of FIG. 8; and,

FIG. 10 is a perspective view thereof showing the forming panel insert in an environment in which it may be used.

The forming panel insert is shown with a symbolic break in its length. The appearance of any portion of the article between the break lines forms no part of the claimed design. The broken lines in FIG. 10 shows portions of the environment that form no part of the claimed design.
